Primary Examiner — Amy C Wierenga*(74) Attorney, Agent, or Firm* — Notaro, Michalos & Zaccaria P.C.(57) **CLAIM**

The ornamental design for a food chopper as shown and described.

DESCRIPTION

FIG. 1 is a top, front right perspective view of a food chopper showing my design;

FIG. 2 is a front view thereof;

FIG. 3 is a back view thereof;

FIG. 4 is a right view thereof;

FIG. 5 is a left view thereof;

FIG. 6 is a top plan view thereof;

FIG. 7 is a bottom plan view thereof; and,

FIG. 8 is a top, front right perspective view of the food chopper in an open position.

The stippling shown in FIG. 7 represents a contrast in appearance.

The broken dash-dot lines represent portions of the food chopper that form no part of the claimed design.
